ASSIGNORS TO THE CONNECTICUT TELEPHONE & ELECTRIC COMPANY, INCOR-
PORATED, OF MERIDEN, CONNECTICUT, A CORPORATION OF CONNECTICUT.

ELECTRIC SWITCH.

Application filed July 17, 1923. Serial No. 652,048.

To all whom it may concern:

Be it known that we, JAMES H. BARTHOLOMEW and RAYMOND H. BOARDMAN, citizens of the United States of America, residing at 5 Meriden, Connecticut, have invented new and useful Improvements in an Electric Switch, of which the following is a specification.

Our invention relates to an electric switch. 10 Among the objects of the invention are to provide an electric switch of simple construction which will be reliable in use, cheap to manufacture, easy to assemble, of sturdy construction, and which will not easily get out 15 of order.

In the drawings, which show, for illustrative purposes only, preferred forms of the invention:

Fig. 1 is a front view of the assembled 20 switch;

Fig. 2 is a rear view thereof;

Fig. 3 is a central vertical section through the switch shown in Fig. 1;

Fig. 4 is a sectional view of a detail;

25 Fig. 5 is a side view in partial section of a modified form of switch.

In said drawings:

1 indicates a body preferably of insulating material and having a passage 2 there- 30 through. The front of the passage may be closed by any suitable or conventional form of face plate secured to the housing or body 1 as by means of screws 4-4. The switch may be secured to a wall or other 35 suitable support by means of screws 5-5 passing through suitable apertures in the face plate.

At the rear of the body 1, two or more 40 fixed contacts 6-7 may be attached as by means of screws 8-9, which may also serve as binding posts for the fixed contacts. In the preferred form shown, the fixed contacts are formed of resilient metal having one 45 end secured by means of the screws 8-9, while the free spring ends extend up into the passage 2.

Across the rear end of the body is a cross 50 bar 10 having an aperture therein. The cross bar may be secured to the body by means of screws 11-11 which may serve as binding posts for the movable contact to be later described. In the preferred form herein disclosed, a guide tube 12 passes through the aperture in the cross bar 10, and

a shoulder thereon abuts one side of the 55 bar. A bushing or thimble 13 is passed over the inner end of the guide tube 12, and the extreme end of the latter is beaded over as at 14 for the purpose of holding the guide tube rigidly to the cross bar 10. A movable contact 15 is secured to the inner end of a guide pin 16, which is slidably mounted in the guide tube 12 and is constrained thereby to move in a straight line. In the form of the invention disclosed in Fig. 3, the movable contact has upwardly extending wings or fingers 17-17 which define a depression or groove therebetween for a purpose to be later described. A spring 18 may be interposed between the cross bar 10 and the movable contact 15 for urging the latter forwardly.

19 indicates generally a bridging contact member for bridging the space between the fixed and movable contacts for closing the 75 circuit between either of the fixed contacts and the movable contact. As herein shown, the bridging contact is mounted on the inner end of an operating lever 20. This lever is pivotally mounted in the body as by means 80 of a pivot pin 21, extending through the lever and seated in suitable bearings or depressions such as 22 in the body. The operating lever is preferably flat, as will be seen from Fig. 1, and the face plate 3 has 85 a suitable opening 23 for the passage of the flat operating lever. The outer end of the lever may be provided with a finger piece 24 for convenience in operation and to give a finished appearance. The inner end of the 90 lever 20 may have an aperture therethrough in which is fitted a bushing 25 of insulating material. A pin 26 extends through the bushing. The metallic bridging contact members 27-28 are mounted on the pin 26, 95 and in the form shown the end of the pin 26 is riveted over on the bridging member 28 and serves to secure both members 27 and 28 to the end of the operating lever. Insulating washers 29 are preferably interposed between the members 27-28 and the operating lever so as to effectually insulate the lever from the bridging contact.

The modification shown in Fig. 5 is substantially the same as the form shown in the 105 other figures, except that in Fig. 5 the movable contact member 30 has its opposite ends turned down, as indicated at 31-31.

All other features in that form are the same as have been previously described.

The operation of the switch is as follows:

Referring to Fig. 3, if the end 24 of the operating lever is moved downwardly as viewed in that figure, the bridging contact 19 rides up along the end 17 of the movable contact 15 and depresses the same against the compression spring 18. When the bridging contact 19 is at about the top of the finger 17, the spring 18, tending to force the finger 17 upwardly, throws the bridging contact upwardly as viewed in Fig. 3 with a snap action, and moves the same to the position indicated in dotted lines in Fig. 3. When it is desired to open the circuit, the finger piece 24 is moved to the full line position shown in Fig. 3, when the bridging contact will be held between the ends 17-17 and the circuit will be opened. When it is desired to close the circuit between the fixed contact 7 and the movable contact 15, the operating lever is moved in a direction opposite to that just described, and the operation will be the same as above set forth.

In the form shown in Fig. 3, the circuit closing bridging member is in a neutral or "off" position as indicated by solid lines; whereas in the form shown in Fig. 5, the circuit closing element 19 will not stand in the position shown in solid lines in Fig. 3, by reason that it travels over a convex face only. The form shown in Fig. 3 is adapted to control two different circuits, with an "off" position between the same. The form shown in Fig. 5 is adapted to control one or the other of two circuits, but instead of providing a circuit through the binding post 9, only one circuit may be provided through the binding post 8, in which event, when the position of the circuit closing element 19 is reversed from that shown in Fig. 5, the circuit will be broken.

In all forms, it will be observed that the circuit closing element moves with a snap action, which is desirable in many cases.

While we have shown certain preferred forms of our invention, we wish it to be understood that modifications may be made without avoiding the scope of the appended claims.

We claim:

1. In an electric switch, a body of insulating material having a passage therethrough, a movable contact member constrained to move in a straight line, a fixed contact, an operating lever pivotally mounted on said body, a bridging contact member mounted on said operating lever and insulated therefrom for bridging said fixed and movable contacts, and means associated with said movable contact for moving said bridging contact member with a snap action.

2. In an electric switch, a body of insulating material having a passage therethrough, a bar at one end of said body and having a guide opening therein, a movable contact member reciprocable in a straight line in said guide member, a fixed contact member on said body, a bridging contact for connecting said fixed and movable contacts, and an operating lever pivotally mounted on said body and secured to said bridging contact.

3. In an electric switch, a body of insulating material, a bar across one end of said body and having an opening therein, a movable contact member slidable in said opening and constrained thereby to move in a straight line, a spring interposed between said movable contact and said bar, a fixed contact member, an operating lever pivotally mounted on said body and having a bridging contact member directly connected thereto for bridging said fixed and movable contacts, said spring serving to throw said bridging contact with a snap action.

4. In an electric switch, a body of insulating material having a passage therethrough, a bar across one end of said passage and having an aperture therein, a guide tube passing through said aperture and rigidly secured to said bar, a movable contact member having a part reciprocable in said guide tube and constrained thereby to move in a straight line, a spring for urging said movable contact in one direction, a fixed contact member, an operating lever pivotally mounted on said body, a bridging contact secured to said operating lever and serving to bridge said fixed and movable contacts, said spring serving to throw said bridging contact with a snap action.

5. In an electric switch, a body of insulating material having a passage therethrough, a resiliently mounted movable contact member in said body and constrained to move in a straight line, a pair of fixed contacts mounted on said body at opposite sides of said movable contact, an operating lever mounted on said body, a bridging contact mounted on said operating lever and serving to bridge the space between either of said fixed contacts and said movable contact.

6. In an electric switch, a body of insulating material having a passage therethrough, a movable contact member in said body, a fixed contact in said body, an operating lever pivotally mounted on said body, a bridging contact rigidly secured to and movable with said operating lever, means for insulating said operating lever and said bridging contact, said bridging contact serving to close the circuit between said fixed and movable contacts.

7. In an electric switch, a body of in-

- sulating material having a passage therein, a bar across one end of said passage and having an aperture therethrough, a guide tube passing through said aperture, a thimble about one end of said guide tube, said guide tube being beaded over said thimble to hold the guide tube in position on said bar, a movable contact having a part 5 slideable in said guide tube and constrained thereby to move in a straight line, a fixed contact member on said body, an operating lever mounted on said body, a bridging contact secured to said lever and serving to bridge said fixed and movable contacts.
- 10 8. In an electric switch, a main body, two fixed contacts carried thereby, a third contact intermediate the first two and includ-
- ing a longitudinally movable plunger, a spring for projecting said plunger, a circuit closing element comprising a bridging 20 member, a pivotally mounted lever carrying said bridging member to move the latter transversely across the path of reciprocation of said plunger and to bridge the space between said plunger and either one of said 25 fixed contacts, said plunger operating to yieldingly hold said bridging member in circuit closing position, the end of said plunger having a recessed portion to hold said bridging member in a neutral or "off" 30 position.

JAS. H. BARTHOLOMEW.
